DESIGN FOR A CHAIR OR SIMILAR ARTICLE

Jackson D. Rogers, Bay Village, Ohio

Application March 17, 1937, Serial No. 68,206

Term of patent 7 years

To all whom it may concern:

Be it known that I, Jackson D. Rogers, a citizen of the United States and resident of Bay Village, in the county of Cuyahoga and State of Ohio, have invented a new, original, and ornamental Design for a Chair or Similar Article, of which the following is a specification, reference being had to the accompanying drawing, forming a part thereof.

In said drawing, Fig. 1 is a perspective view of a chair, showing my design, the characteristic feature of which resides in the seat and back members shown in full lines; and Figs. 2 and 3 are cross-sectional views of two portions of the seat member of the chair, on the lines 2—2 and 3—3, respectively, of Fig. 1, and also cross-sectional views of two portions of the back member of the chair, as taken on the lines 2'—2' and 3'—3' of Fig. 1, such seat and back members being of identical contour.

I claim:

The ornamental design for a chair or similar article, as shown and described.

JACKSON D. ROGERS.
